UNITED STATES PATENT OFFICE.

FREDERICK G. SHULL, OF CONCORD, MASSACHUSETTS, AND ELON J. DE RIGHT, OF KANSAS CITY, MISSOURI.

GUYING-POLE.

1,257,135.

specification of Letters Patent. Patented Feb. 19, 1918.

Application filed August 27, 1917. Serial No. 188,372.

To all whom it may concern:

Be it known that we, FREDERICK G. SHULL and ELON J. DE RIGHT, citizens of the United States, residing at Concord, county 5 of Middlesex, Commonwealth of Massachusetts, and Kansas City, county of Jackson, State of Missouri, respectively, have invented certain new and useful Improvements in Guying-Poles; and we do hereby declare 10 the following to be a full, clear, and exact description of the invention, such as will enables others skilled in the art to which it appertains to make and use the same.

The present invention relates to means 15 for supporting and guying poles and more particularly to devices of this character employed for guying poles which carry wires and cables.

It is customary to brace and support this 20 type of pole through a guy extending diagonally from the pole to the ground and having its ends secured by some form of clamp which is intended to prevent slackening of the guy wire. The form of clamp most generally employed is made in two pieces between which the length of the guy wire and the free end pass and are clamped in place by several bolts, the number depending upon the size of the guy wire and the strain imposed thereon. This type of clamp is unsatisfactory as it is expensive to manufacture, 25 does not absolutely insure against slackening of the guy wire, and does not facilitate the removal of the guy wire when so desired. A number of clamps have been devised intended to overcome the disadvantages of the bolt type of clamp above described, but all of these constructions are expensive and inefficient, and with the exception of the bolt clamp, none of them have gone into extensive use.

One object of the present invention is to provide improved means for guying and bracing a post which is inexpensive to manufacture and may be readily assembled when setting up the post to put the requisite tension upon the guy wire.

A further object of the invention is to provide an improved form of clamp for a 45 guy wire which insures against any slackening of the guy wire after the post has been set up and the guy wire initially put in tension but which may be easily disconnected from the guy wire when desired to

permit the removal of the latter from the 55 post.

With the above objects in view the several features of the invention consist in certain novel features of construction, combinations and arrangements of parts hereinafter described and claimed, the advantages of which will be obvious to those skilled in the art from the following description.

In the accompanying drawings illustrating the preferred form of the invention, 65 Figure 1 represents an elevation of a pole having the improved guying means attached thereto; Fig. 2 is a detail illustrating a side elevation of the improved clamp with the guy wire passing therethrough; Fig. 3 is a 70 top plan view of the clamp shown in Fig. 2; Fig. 4 is a detail showing a cross section upon the line 4-4 of Fig. 3; Fig. 5 is a cross section upon the line 5-5 of Fig. 3; Fig. 6 is a cross section upon the line 6-6 75 of Fig. 3; and Fig. 7 is a cross section upon the line 7-7 of Fig. 3 showing the detachable connection between the lug and base of the clamp.

In the illustrated embodiment of the invention a telephone or electric light pole is indicated at 1, having cross arms 2 which carry the usual insulators 3. This pole is braced by a guy wire indicated generally at 5, and extending diagonally from a point 80 between the two cross arms to the ground, as shown clearly in Fig. 1.

According to the present invention the opposite ends of the guy wire are looped through suitable connecting members and 90 the free end of the loop is clamped in each case to the length of the guy wire by an improved form of clamp which provides for a convenient assembling of the guy wire with the pole and permanently retains the 95 guy wire in position after the initial tension has been put thereon. Upon referring to Fig. 1 it will be noted that the upper end of the guy wire is passed through the eye 10 of a bolt 11 which passes through the 100 pole 1 and is secured at its opposite end by a nut 12. The opposite or lower end of the guy wire is connected to a suitable anchoring device 15 embedded in the ground and provided with an eye bolt 16 through which 105 is passed a suitably shaped thimble 17 connected directly to the guy wire clamp.

The free end of the guy wire is clamped to

the length of the wire by a simple and efficient form of clamp which permits an initial adjustment of the wire to take up slack and positively locks the wire immediately upon the removal of the slack and the placing of the wire under tension. To this end a clamp 20 is designed for the reception of opposite sides of the loop of guy wire, the clamp having a base portion 21 upon which the wire 5 rests and projecting lugs 22, 23 and 24 about which opposite sides of the bight of wire pass, as will be more fully described hereinafter. The length 25 of the guy wire forming one side of the bight passes into the 10 clamp at the right of the lug 22, next passes about the left side of the lug 23, and finally about the right side of the lug 24, from which it passes to the pole, as shown clearly in Fig. 3. The free end 26 forming the opposite side of the bight enters the clamp at the left side of the lug 24, then passes beneath the length of the wire about the right side of the lug 23, again beneath the length 15 of the wire, and finally extends out of the clamp at the left side of the lug 22. This construction causes the length 25 of the guy wire to bind upon the free end 26 of the wire at the two points of intersection 27 and 28 when the guy wire is put in tension. With 20 this construction in order to initially put tension on the guy wire it is only necessary to pull upon the free end 26 which is permitted to reeve freely through the clamp until the slack is completely taken out of the 25 guy wire, when the length 25 of the wire binds upon the free end at the points of intersection 27 and 28, preventing not only further movement of the latter to tighten the guy wire, but in addition locking the free 30 end of the wire in place to prevent any subsequent slackening of the guy wire. In order to augment the gripping effect of one side of the bight of wire upon the other each of the lugs 22, 23 and 24 is provided with 35 a cam face 30 shaped in accordance with the particular size and shape of the guy wire to force the guy wire passing thereabout into the junction of the lug with the base portion 21 of the clamp. The advantages of this 40 construction will be readily apparent from an inspection of the drawings where it will be observed that the greater the strain upon the guy wire the greater the tendency to press the length 25 of the wire against the 45 free end 26. In order to prevent the pressure of the upper length of wire from flattening out the under length of wire at the points of intersection and in consequence impairing the strength of the wire, the base 21 50 of the clamp is provided, as shown clearly in the drawings, with a shallow groove 32 extending between the lugs and adapted for the reception of the free end 26 of the wire, which is clamped between the length of the 55 wire and the base. This recess or groove is 60

not of sufficient depth to interfere with the clamping action of the upper length of wire 25 but is of sufficient depth to aid the free end of the wire in retaining its shape, preventing separation of the strands and consequent weakening of the wire. From an inspection of Figs. 1 and 3 of the drawings it will be noted that the lug 22 is slightly offset from the center line of the clamp so that the length 25 of the wire passes from the lug 70 23 to the lug 22, and thence off of the clamp without abrupt bends. In the construction shown in the drawings both the upper and lower clamps are substantially identical except that the lower clamp is provided with a tail piece 33 having an opening adapted to receive the bolt 34 of the thimble 17. In assembling the guy wire with the upper clamp, a ring 37 is conveniently slipped over the bight of wire between the pole and the 80 clamp, as shown in Fig. 1, and serves to hold the opposite sides of the bight in contact with the lug 24, thus increasing the efficiency of the clamp.

It will be obvious to those skilled in the 90 art that the improved form of clamp serves to permanently maintain the proper tension upon the guy wire and effectually prevents slippage of the free end 26 of the wire through the clamp. According to the usual 95 practice the tension upon the length 25 of the wire is sufficiently great to prevent the withdrawal of the free end 26 of the wire from the clamp without the use of some form of tackle for first removing the tension from the wire. In order to permit the 100 convenient removal of the guy wire from the pole, means are provided for relieving the pressure of the upper side of the loop of wire upon the lower side and to this end 105 the lug 23 is made as an independent member detachably connected to the base 21. The lug is provided with a V-shaped tongue 28 projecting from the bottom of the lug and adapted to be received in a corresponding 110 groove 40 extending lengthwise of a boss 41 formed upon the base. The groove 40 is closed at both ends by the boss and the coöperated tongue and groove thus position the lug both laterally and longitudinally 115 with relation to the base. A bolt 42 passes through the lug and base and is secured in place by the usual form of clamping nut 43 engaging with the bottom of the base. With this construction the guy wire is 120 normally locked in the clamp after the initial assembling but the subsequent removal of the wire is conveniently accomplished by detaching the lug from the clamp. This immediately relieves the pressure of the length 125 25 of the wire upon the free end 26 at the points of intersection and permits the wire to be disengaged from the clamp.

While it is preferred to employ the specific construction and arrangement of parts 130

shown and described, it will be understood that this construction and arrangement is not essential except so far as specified in the claims, and may be changed or modified 5 without departing from the broader features of the invention.

The invention having been described, what is claimed is:

1. Means for guying poles, comprising 10 a fixed connector, a guy wire having an end looped through the connector, and a clamp having a base and a plurality of separated lugs projecting from the base about which the two sides of the loop pass in opposite 15 directions with the length of the wire positioned above the free end of the wire, the faces of the lugs being constructed and arranged to crowd the length of the wire, toward the base to clamp the free end of 20 the wire when the length of the wire is under tension.

2. Means for guying poles, comprising a fixed connector, a guy wire having an end looped through the connector, a clamp having 25 a plurality of separated lugs about which the two sides of the loop pass in opposite directions with the length of the wire positioned above the free end of the wire, the faces of the lugs being constructed and arranged to crowd the length of the wire upon 30 the free end of the wire when the length of the wire is under tension, and a ring interposed between the clamp and connector to retain opposite sides of the loop in contact 35 with the adjacent lug.

3. Means for guying poles, comprising a 40 clamp having a base portion, a lug projecting from the base between the ends and having the opposite sides of a loop of wire passed thereabout, and a second lug positioned at the end of the clamp and slightly offset from the center line of the clamp to permit a wire 45 to extend from the center lug to the opposite side of the end lug and thence off of the clamp without abrupt turns, each of the lugs being provided with cam faces constructed and arranged to crowd a wire passing thereabout into the junction between the lug and the base.

50 4. Means for guying poles, comprising a clamp having a base portion, a plurality of separated lugs extending from the base, a groove formed in the base and extending from the side of one lug to the opposite side of the next adjacent lug, each of the lugs having a cam face adapted to crowd a wire passing thereabout toward the base, and a loop of wire received in the clamp, the

free end of the loop passing about opposite sides of adjacent lugs and lying in the 60 groove in the base and the length of the wire forming the opposite side of the loop extending about the opposite side of each lug and crossing the free end of the loop between adjacent lugs. 65

5. Means for guying poles, comprising a clamp having a base portion, three separated lugs positioned lengthwise of the base portion and each having a cam face adapted to force a wire passing around the lug toward the base, and detachable connections between the center lug and the base to permit the removal of the lug from the base 70 when desired.

6. Means for guying poles, comprising a 75 clamp having a base portion, a lug secured to the base and having a cam face adapted to press a wire passed around the lug toward the base, tongue and groove connections between the lug and base, and a bolt 80 passed through the lug and base to secure the lug to the base.

7. The combination with a guy wire for poles, of means for holding the looped end of the wire comprising a clamp having a 85 base portion and a plurality of lugs formed thereon with the free end of the loop of wire lying against the base portion and passing about opposite sides of successive lugs and the length of the wire passing about each 90 lug upon the side opposite the free end and bearing upon the free end between each pair of lugs to clamp the free end of the wire against the base when the length of the wire 95 is in tension.

8. A clamp for guy wires, comprising a base portion, a plurality of lugs projecting from the same side of the base portion and separated from one another lengthwise of the clamp and adapted to have opposite 100 sides of a bight of wire passed therearound crossing between each pair of lugs, each lug having a cam face constructed and arranged to force the wire passing about the lug into the junction between the lug and the base 105 when the wire is placed under tension.

9. A clamp for guy wires, comprising a base portion, a plurality of separated lugs supported upon the base and adapted to have opposite sides of a bight of wire passed 110 therearound crossing between each pair of lugs, and means for detachably connecting one of the lugs to the base portion to permit the guy wire to be released from the clamp.

FREDERICK G. SHULL.
